UNITED STATES PATENT OFFICE.

FREDERICK EDWARD HODDERSEN-BALLING, OF BROOKLYN, NEW YORK.

MEAT-SLICING MACHINE.

1,235,318.

Specification of Letters Patent. Patented July 31, 1917.

Application filed March 6, 1912. Serial No. 681,900.

To all whom it may concern:

Be it known that I, FREDERICK EDWARD HODDERSEN-BALLING, a citizen of the United States, and a resident of Brooklyn, in the 5 county of Kings and State of New York, have invented certain new and useful Improvements in Meat-Slicing Machines, of which the following is a specification.

This invention relates to meat slicing machines, having reference more especially to that well-known class of machines which include in their construction a relatively reciprocating meat supporting table and a rotary cutting disk arranged in coöperative 15 relation to each other, whereby a body of ham, or the like, which is supported on the table in such position as to project forwardly beyond the lateral vertical plane of the cutter, may be fed into and across 20 the path of the latter and the forwardly projecting portion of the body thus be progressively sliced therefrom.

The object of my invention is to provide for machines of the character mentioned a 25 novel abutment structure which is mounted and arranged on the reciprocating table in position to bear against and support in opposition to the thrust of the cutter the outer lateral portion of the ham, etc., 30 throughout the entire slicing operation, whereby a uniform and efficient severance of the slice from the body is effected without any liability of the slice, when partially severed, being prematurely torn or broken 35 off. To this end, my invention, as generally stated, comprises various novel features of construction and combinations of parts which will be hereinafter described and claimed.

40 In the drawings—

Figure 1 is a front elevation of a meat slicing machine equipped with my abutment structure, only so much of the machine being shown as is necessary to illustrate my 45 invention.

Fig. 2 is a perspective view of the structure, detached.

A indicates a horizontally movable table upon which the ham or other body of meat 50 to be sliced is supported immediately upon the feed-plate a'' , which is automatically fed forward on the guides a''' ; B a rotary cutting disk into the path of which the said body is progressively fed and across which 55 it is reciprocated by the table in its travel; and C a driving shaft which is operatively connected with the cutter and the table so that actuation of the shaft effects the rotation of the cutter and the reciprocation of the table. The connection between the 60 driving shaft and the cutter includes the sprocket gearing b ; and the connection between the shaft and the table includes the connecting rod a and the crank a' of the driving gear. As this mechanism is of well-known construction and operation it is not deemed necessary herein to show or describe the same in detail. For a fuller understanding thereof reference may be had to United States Patent No. 920,506, dated 70 May 4, 1909.

My invention, which is designed more particularly as an attachment for any slicing machine of the character above referred to, comprises essentially an abutment member which is secured to the movable table A in such manner as to support against horizontal thrust the outer side of the ham or other body as the slice is being severed by impact with the cutter. The said member 75 is arranged to travel with the table toward the cutter and thus to counteract the thrust of the cutter until the slice has been completely severed. This abutment member is not attached to the feed plate a'' and does 80 not interfere with its forward movement.

The abutment member in its preferred construction comprises a vertically disposed plate 1 shaped to conform with the opposing outer side of the body of meat against which 85 it impinges. In the present instance the plate is illustrated as curved to present a substantial bearing surface to the side of a ham for instance, and the rearward edge of the plate as flared slightly outward (as at x) 90 to permit the free forward feeding of the ham preparatory to the severance therefrom of a slice of predetermined thickness. The lower part of the plate 1 has affixed thereto a laterally extending bar 2 which is slidably 95 fitted to horizontal apertures 3 in the arched upper portion of a vertical bracket 4 which is affixed, as by bolts 5, to the outer end of the movable table A, that is, the end remote from the cutter. The bar is slidably fitted 100 to a horizontally perforated clamp block 6 which is located within the arched portion of the bracket and is provided with a vertical screw shank 7. This shank extends freely through an aperture in the top of the 105 bracket and is equipped on its outer portion with an ordinary thumb-nut 8, by the ma-

nipulation of which the clamp block may be raised to clamp the shank fixedly to the bracket, or be depressed to release the shank. When the nut is unscrewed from the top of the bracket the shank, being free from the clamping action of the block, may be moved longitudinally in order to set the abutment member firmly against the opposing side of the body supported on the feed plate a'' of the table A, and then by rescrewing the nut the shank and its abutment member may be securely clamped and held in the position of adjustment.

From the foregoing it will be seen that my invention provides a simple and efficient structure which effectually supports the outer side of the ham or other body of meat during the cutting operation, and thereby obviates any liability of the outer edge of the slice breaking off or ragging before it has been completely severed by the edge of the cutter. Although the cutter disk B is shown on a fixed axis while the table A is shown as reciprocating, it is of course understood that it is necessary merely that the parts A and B relatively reciprocate.

It is to be understood that my invention is not limited to the specific details of construction herein shown and described.

I claim—

In a meat-slicing machine, a relatively reciprocative rotary cutter and a meat supporting table; a flat feed-plate feedably slideable on said table in a direction lateral to the relative reciprocation of said cutter and table; means secured to the feed-plate for clamping the meat directly upon said feed-plate and comprising a member extending up at the side of the plate and a member extending across the meat-plate; an upright bracket fixed to the meat-table out of the path of travel of said feed-plate and clamping means; a horizontally extending shank adjustably secured to said bracket and extending over said feed-plate; and an enlarged rearwardly flared meat-abutment carried by the inner end of said shank and disposed over said feed-plate out of contact therewith, said abutment being entirely independent in its support from said feed-plate and fixed in position relatively to said meat-supporting table.

Signed at New York, in the county of New York, and State of New York, this fifth day of March A. D. 1912.

FREDERICK EDWARD HODDERSEN-BALLING.
